CLAIM

The ornamental design for a door lock plate, as shown and described.

DESCRIPTION

FIG. 1 is a front elevational view of my new design of a door lock plate;

FIG. 2 is a right side elevational view of my new design of the door lock plate with a left side elevational view of the door lock plate being a mirror image thereof;

FIG. 3 is a bottom view of my new design of the door lock plate with a top elevational view of the door lock plate being a mirror image thereof;

FIG. 4 is a rear elevational view of my new design of the door lock plate; and,

FIG. 5 is a perspective view of my new design of the door lock plate.

*FIG. 1**FIG. 2**FIG. 3*

FIG. 4

FIG. 5
